(57) **CLAIM**

The ornamental design for an combined aroma diffuser and clock, as shown and described.

DESCRIPTION

FIG. 1 is a front perspective view of an combined aroma diffuser and clock, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged detail view of area 8 in FIG. 1.

The broken lines depict portions of the combined aroma diffuser and clock that form no part of the claimed design.

1 Claim, 8 Drawing Sheets
